UNITED STATES PATENT OFFICE.

FRANK E. CROTTO, OF TULSA, OKLAHOMA, ASSIGNOR TO WESTERN SUPPLY COMPANY,
OF TULSA, OKLAHOMA.

WIRE LINE CLAMP.

Application filed June 18, 1923. Serial No. 646,283.

To all whom it may concern:

Be it known that I, FRANK E. CROTTO, citizen of the United States of America, residing at Tulsa, in the county of Tulsa and 5 State of Oklahoma, have invented certain new and useful Improvements in Wire Line Clamps, of which the following is a specification.

This invention relates to new and useful 10 improvements in wire line clamps.

The object of this invention is to provide a wire line clamp in which the clamping elements will, when brought into operation, exert an equal pressure on the line radially 15 toward the center of said line; and which when released will relieve the pressure radially from the center of the line; whereby the line is saved from distortion and said elements will be prevented from wedging 20 or locking and a free and easy operation is attained.

A further object of the invention is to provide a wire line clamp in which the pressure exerted by the clamping elements may 25 be equally and gradually applied or relieved.

A further object is to provide a device of the character described, in which the adjustment of the clamping elements may be minutely controlled so that any desired 30 slip-page of the line may be effected to a predetermined degree.

An advantage of the invention results from the use of a plurality of line slips which being subjected to an equal wear upon 35 their work faces, are not only interchangeable, one with the other, but may be replaced from stock parts and all made from the same pattern.

A construction designed to carry out the 40 invention will be hereinafter described together with other features of the invention.

The invention will be more readily understood from a reading of the following specification and by reference to the accompanying drawings, in which an example of the 45 invention is shown, and wherein:

Fig. 1 is a plan view of a clamp constructed in accordance with my invention, portions being illustrated in section,

50 Fig. 2 is a side elevation of the same,

Fig. 3 is a transverse sectional view on the line 3—3 of Fig. 1,

Fig. 4 is a detail of the swivel nut, and 55 Fig. 5 is a detail of the handle fastening.

In the drawings the numeral 10 designates 55 an arcuate head having vertical side or end webs 11, and a central web 12 connecting its top and bottom plates, pockets being formed on each side of the central web. Elongated clamp arms 13, each have an ear 14 on their 60 inner ends engaging in one of the pockets. The ears are reduced in thickness so as to enter the pockets between the top and bottom plates of the head and are pivoted on vertical pins 15 fastened in said plates. 65

The arms are shouldered on top and bottom immediately in front of the head and each has a vertical arcuate seat 16, which is given length by the shoulders. In the end of 70 the web 12 and the front is formed an arcuate seat 16'. These seats are in concentric relation and each receives a slip 17, the latter being duplicates and interchangeable. The seats have sumps 18 for receiving bosses 19 on the inner sides of the slips. Bolts 20 are 75 passed through the web 12 and arms 13 and have their ends threaded in the bosses and the slips, whereby the latter are held in place. The slips have outwardly directed flanges 17' at their upper ends overhanging 80 the arms and the head. The faces of the slips are formed on radius less than that of the cable or rope which is to be clamped. The arms outwardly of the seats have opposed arcuate grooves 21 for receiving a 85 smaller rope or line.

The arms have upwardly and outwardly curved hooks 22 overhanging the sides of the head and receiving links 23, whereby the clamp may be suspended in the usual 90 manner. The arms have their adjacent sides diverging and their outer ends slotted. In the end of one arm a cylindrical nut 24 is journaled and has its end headed and countersunk as is shown in Fig. 4. A latch bolt 95 25 is threaded through the nut and by the arrangement shown in Fig. 4, the bolt is centered in the slotted end of the right hand arm (Fig. 1). The left hand end of the bolt is reduced at 26 to form a shoulder 27. 100 A portion of the reduced end has projecting screw threads 26' spaced from the shoulder. A washer 28 is threaded over the threads and located in the space between the latter and the shoulder in which it is loosely 105 confined. A flanged nut 29 is screwed onto the threads and fastened with a set screw 31. Ball bearings 30 are interposed between

the nut and the washer to take the thrust and to permit the nut to be burned by the bolt 25.

The washer bears against the outerside of the left hand arm 13 and on the right hand end of the bolt is mounted a handle 32. By turning the handle the bolt 25 is rotated and moved longitudinally through the nut 24. By turning the handle in a counter clockwise direction the bolt moves toward the left hand (Fig. 1) arm and the washer 28 is freed so that the arms are released and the bolt may be swung out of the end of the left hand arm. By turning the handle in a clockwise direction the arms are drawn together.

In using the links 23 are suspended by the usual manner. The bolt 25 is swung out of the end of the left hand (Fig. 1) arm and the arms opened, whereby the slips 17 are spread apart on each side of the central slip 17 carried by the head. The throat which is thus opened readily receives the cable and the latter is disposed between the slips.

After the cable is received the bolt 25 is swung into the arm and the handle 32 turned until the washer bears against the outer side of the left hand arm; whereupon further rotation of the bolt serves to draw the arms together. As the arms are swung together on their pivot pins 15, the slips 17 carried by said arms engage the cable and clamp it against the central slip. It will be seen that the arm slips engage the cable on each side and gradually and uniformly in conjunction with the center slip, clamp said cable, with the result that the cable is not rolled, twisted or distorted, but is firmly engaged with an equal radial pressure toward its center. This is due to the relative location of the centers of the pivot pins 15 with relation to the slips.

The cable may be very tightly engaged without injury. By turning the bolt 25, the arms may be spread to just loosen the slips enough to permit a desired slippage of the cable. This may be minutely controlled owing to the length of the arms and the pitch of the threads of the bolt. The slips being released with substantially equal pressure it is obvious that their faces will wear equally. There will be no unequal wear or eccentric gripping action in this clamp and the cable will be at all times and under all conditions efficiently held by the clamp.

Various changes in the size and shape of the different parts as well as modifications and alterations may be made within the scope of the appended claims.

What I claim, is:

1. In a line clamp, a head, a clamping slip carried by the head, a pair of co-acting arms pivoted to the head, and slips carried by the arms and correlated to the head slip.

2. In a line clamp, a head, a clamping slip carried by the head, a pair of co-acting arms, pivoted to the head, slips carried by the arms and correlated to the head slip and means for drawing the arms together for bringing the slips into clamping relation. 70

3. In a line clamp, a head having cable line receiving portion, a pair of arms pivoted to said head, each having an arcuate cable line clamping element co-acting with the line receiving portion of the head when the arms are swung together. 75

4. In a line clamp, a head having cable line receiving portion, a pair of arms pivoted to said head, each having an arcuate cable line clamping element co-acting with the line receiving portion of the head when the arms are swung together, and means for drawing said arms together. 80

5. In a line clamp, a head having a cable clamping element and clamping arms pivoted to the head on each side of the clamping element, cable clamping means carried by the arms on each side of the clamping element. 85

6. In a line clamp, a head having a cable clamping element, clamping arms pivoted to the head on each side of the clamping element, cable clamping means carried by the arms on each side of the clamping element, and means for drawing the arms together. 90

7. In a line clamp, a head having a cable clamping element, clamping arms pivoted to the head on each side of the clamping element, cable clamping means carried by the arms on each side of the clamping element, and means for drawing the arms together, said last named also acting to gradually release the arms to uniformly relieve the clamping pressure of the arms. 100

8. In a line clamp, a head having a central cable clamping element, clamping arms pivoted to the head on each side of said element, cable clamping means on each arm adjacent the clamping element and adjacent each other, and a latch bolt swiveled in the outer end of one arm and carrying means for engaging the other arm for fastening said arms together and for drawing them into clamping relation. 110

9. In a line clamp, a head having an elongated vertical cable clamping element arcuate in cross-section, clamping arms pivoted to the head on each side of the clamping element, elongated cable clamping means on each arm adjacent the clamping element, said clamping means being arcuate in cross-section, the pivot points of the arms and the clamping element and clamping means being so related that when said arms are swung the said element and means are brought into concentric clamping relation, and means for drawing the arms together and fastening them. 120

10. In a line clamp, a head having an 125

elongated vertical seat at its center, a slip
removably mounted in the seat of the head,
clamping arms having ears pivoted in the
head on each side of the seat, hooks carried
by the arms for suspending the clamp, the
arms having vertical seats, removable slips
mounted in the seats of the arms, a latch

bolt pivoted in the outer end of one of the
arms, and adapted to engage in the other
arm, a handle mounted on the bolt, and 10
means on the bolt for engaging the other
arm.

In testimony whereof I affix my signature.
FRANK E. CROTTO.
